HANGING PLANTER

Raymond Godfrey Souder, 808 NW. 1st Ave.,
Fort Lauderdale, Fla. 33311

Filed Oct. 23, 1970, Ser. No. 25,609

Term of patent 14 years

Int. Cl. D11—02

U.S. Cl. D35—3

FIG. 1 is a side view of the hanging planter, showing my new design;

FIG. 2 is an enlarged view of the trays of the hanging planter; and

FIG. 3 is a view as seen along the line 3—3 of FIG. 2.
I claim:

The ornamental design for a hanging planter, substantially as shown and described.
